(57) **CLAIM**

The ornamental design for a gaming machine pedestal as shown and described.

DESCRIPTION

FIG. 1 is a right perspective view of a first embodiment of a gaming machine pedestal showing the new design.

FIG. 2 is a left perspective view of the gaming machine pedestal shown in FIG. 1.

FIG. 3 is a front view of the gaming machine pedestal shown in FIG. 1.

FIG. 4 is a rear view of the gaming machine pedestal shown in FIG. 1.

FIG. 5 is a right side view of the gaming machine pedestal shown in FIG. 1.

FIG. 6 is a left side view of the gaming machine pedestal shown in FIG. 1.

FIG. 7 is a top view of the gaming machine pedestal shown in FIG. 1.

FIG. 8 is a bottom view of the gaming machine shown in FIG. 1.

FIG. 9 is right perspective view of the gaming machine pedestal shown in FIG. 1 with broken line environment thereon.

FIG. 10 is a right perspective view of a second embodiment of a gaming machine pedestal showing the new design.

FIG. 11 is a left perspective view of the gaming machine pedestal shown in FIG. 10.

FIG. 12 is a front view of the gaming machine pedestal shown in FIG. 10.

FIG. 13 is a rear view of the gaming machine pedestal shown in FIG. 10.

FIG. 14 is a left side view of the gaming machine pedestal shown in FIG. 10.

FIG. 15 is a right side view of the gaming machine pedestal shown in FIG. 10.

FIG. 16 is a top view of the gaming machine pedestal shown in FIG. 10.

(Continued)

FIG. 17 is a bottom view of the gaming machine shown in FIG. 10; and,

FIG. 18 is a right perspective view of the gaming machine pedestal shown in FIG. 10 with broken line environment thereon.

The dash-dot broken lines in FIGS. 2, 8, 11, and 17 depict the bounds of the claimed design, while the dashed broken lines in FIGS. 9 and 18 are directed to environment. The broken lines form no part of the claimed design.
